LOCK FOR BRAKE LEVERS

Original Filed June 24, 1922

Inventor.

Forest W. Gillette,
by his attorney,
Charles R. Seale

UNITED STATES PATENT OFFICE.

FOREST W. GILLETTE, OF HOBOKEN, NEW JERSEY.

LOCK FOR BRAKE LEVERS.

Application filed June 24, 1922, Serial No. 570,739. Renewed November 1, 1934.

To all whom it may concern:

Be it known that I, FOREST W. GILLETTE, a citizen of the United States, residing at Hoboken, in the county of Hudson and State of New Jersey, have invented a certain new and useful Improvement in Locks for Brake Levers, of which the following is a specification.

The invention relates to devices for locking the brake-lever of a motor vehicle with the brake mechanism in the "set" condition to prevent movement of the vehicle until the lever is unlocked to permit the brake to be again released, and the object of the invention is to provide a device of this character which may be easily applied to the usual brake mechanism without altering the latter, and which shall be simple in construction and operation and serve reliably in preventing the movement of the vehicle by unauthorized persons.

The invention consists in certain novel features and details of construction and arrangement by which the above objects are attained, to be hereinafter described and claimed.

The accompanying drawings form a part of this specification and show an approved form of the invention.

Figure 1 is a front elevation of a brake-lever and its immediately adjacent parts and connections, equipped with the improved locking means, and partly in vertical section.

Figure 2 is a corresponding side view.

Figure 3 is a plan view showing the brake-lever sector and the locking-bolt bar alone.

Similar reference numerals indicate the same parts in all the figures.

The brake-lever 5 is mounted on a stud 6 and carries a brake-rod 7 pivotally connected thereto at 8 and extending to the brake mechanism of the vehicle, not shown. The brake-lever 5 also carries at its lower end a spring actuated pawl 9 operated by the release rod 10 and hand piece 11 pivoted to the handle 12 of the lever. The nose of the pawl engages in the notches between the teeth 13 of a sector 14 located below the stud 6 and fixedly secured to the chassis or portion of the vehicle frame by bolts 15.

All these parts may be as usual or of any approved construction and operate in the usual manner.

55 Parallel with and alongside the sector 14

is a curved bar 16 held by the same bolts 15 and having a series of cavities 17 in its upper face, spaced to correspond to the notches in the sector, and on the outer face of the lever 5 is a long locking-bolt or rod 18 mounted to slide thereon in guides 19 and having a nose 20 adapted to engage either of the cavities 17 when presented in alignment therewith in accordance with the position of the pawl 9 and lever 5.

The upper end of the bolt 18 enters the casing 21 of a lock 22, the mechanism of which is not shown but may be understood to be of the Yale or other type, the bolt 22 being connected with the head 18a of the bolt 18, as shown in Figure 1, and the whole arranged to lower or raise the bolt 18 into or out of engagement with the cavities 17, and when thus lowered to hold the bolt in such engagement until released and lifted by the application of the key to the lock.

By applying the brake strongly and locking the bolt 18 in the corresponding cavity, the vehicle cannot be moved until the bolt is again withdrawn and the lever freed.

A light spring 23 may be employed to lift the bolt 18 and thus aid in the unlocking operation.

It will be observed that the bar 16 is located below the floor 24 of the vehicle and concealed by the side thereof, as at 25, so that the point of engagement of the bolt with its bar is practically inaccessible and these parts are thus protected against the application of tools or appliances for the purpose freeing the lever by attacks upon the bolt.

I claim:

In a device of the character set forth, a pivotally mounted brake-lever, a pawl pivotally mounted thereon, a toothed segment, a member disposed parallel therewith and having cavities corresponding to and arranged by the side of said teeth, said pawl being cooperable with said teeth, a locking rod movably mounted on said lever for cooperation with said cavities, a lock, a member of which is connected with said locking rod to throw it in one direction, and a spring acting on said rod to assist in its movement in the opposite direction.

In testimony that I claim the invention above set forth I affix my signature.

FOREST W. GILLETTE.
